UNITED STATES PATENT OFFICE.

CLARENCE W. CARTER, OF MINNEAPOLIS, MINNESOTA, ASSIGNOR TO CARTER-MAYHEW MANUFACTURING COMPANY, OF MINNEAPOLIS, MINNESOTA, A CORPORATION OF MINNESOTA.

SCALPER.

Application filed August 27, 1924. Serial No. 734,423.

To all whom it may concern:

Be it known that I, CLARENCE W. CARTER, a citizen of United States, residing at Minneapolis, in the county of Hennepin and State of Minnesota, have invented certain new and useful Improvements in Scalpers; and I do hereby declare the following to be a full, clear, and exact description of the invention, such as will enable others skilled in the art to which it appertains to make and use the same.

My present invention provides a highly efficient grain scalper and cleaner and, generally stated, it consists of the novel devices and combinations of devices hereinafter described and defined in the claims.

It is a well known fact that grain, as it comes to the elevator from the farmer, nearly always contains a large amount of foreign material such as stalks, pieces of binding twine, straw, dust, small seeds and the like, and sometimes even nails or pieces of iron, bark and twigs. Wheat is almost always mixed with oats, barley and other seeds that may be separated from the clean wheat by fanning mills or grain separators already in use for such purpose; but before the grain can be properly presented to such separators the foreign materials such as above enumerated should be removed, and for this purpose vibratory scalping screens have hitherto been used. These vibratory scalping screens do not do the best of work largely for the reason that the vibratory movement will upon such articles as nails, sticks and the like and allow the same to pass through the necessarily large meshes of the scalping screen.

I have found that I can accomplish the scalping action desired in a much more effectual manner than by the use of vibratory scalping screens by the use of a drum-like rotary scalping screen having large meshes and by an arrangement whereby the grain will flow freely through this rotary screen into the interior thereof and then downward and outward of the same. A rotary screen of this character even when the meshes are very large will carry over all objects such as sticks, straws, nails and other large or relatively long foreign materials for the reason that it will, upon initial engagement therewith, turn such objects substantially tangential to the cylindrical or drum-like surface of the screen and cause them to ride over the top of the screen to the point of

discharge from the screen, providing the stock or material is caused to bank up within the rotary screen, so that the upwardly moving portions of the screen will be caused to force their way up through a bank or accumulated portion of the stock. This banking up of the stock is essential, for otherwise, long objects, such as sticks, nails, straws and the like, would pass on through the screen with the good stock and would not be diverted from their course or thrown into substantially tangential contact with the screen and carried over the screen, as is required for the proper separation. From the statements just made, it follows that the supply of the stock to the rotary screen should be freer than the discharge of the stock from the screen. The best means for affording this desired supply and discharge is an upper hopper with an adjustable gate, and a lower hopper with an adjustable gate, the said lower hopper being arranged closely under the screen where it will receive and hold up the stock for proper accumulation within the rotary screen.

The drum-like rotary screen is preferably arranged to revolve on a horizontal axis, and in association therewith I provide a primary hopper or receptacle arranged to deliver the grain and foreign materials to the upwardly moving side of the screen, and a secondary hopper or receptacle arranged to receive the grain that is passed through the rotary screen and from which the large foreign materials have been removed.

Preferably, I also employ a grain cleaner of the aspirator type which includes a suction fan and a depending air stalk, through which latter the grain from the rotary scalping screen or from the secondary hopper is arranged to drop so that light foreign materials such as dust, light chaff, small, light seeds and the like that are not removed from the grain by the scalping machine will be picked up and carried from the grain.

The operations just outlined will leave wheat, for example, clean except for oats, rye or barley and the like, or possibly some of the smaller and very heavy seeds; but all of these materials can be effectually separated by grain separators now in use and particularly by that type of rotary grain separator known as the Carter-Mayhew disc separator.

The accompanying drawings illustrate a

commercial form of the machine designed to operate as a scalper and cleaner or aspirator. In the said drawings, like characters indicate like parts throughout the 5 several views.

Referring to the drawings:

Fig. 1 is a view chiefly in front elevation but with some parts sectioned on the line 1—1 of Fig. 2, showing the improved machine;

Fig. 2 is a section on the line 2—2 of Fig. 1;

Fig. 3 is a detail in transverse section on the line 3—3 of Fig. 2;

Fig. 4 is a fragmentary side elevation of the parts shown in Fig. 3, looking at the same from the right toward the left;

Fig. 5 is a detail in horizontal section on the line 5—5 of Fig. 4;

Fig. 6 is a side elevation of the parts shown in Fig. 3 looking at the same from the left toward the right, and with some parts sectioned on the line 6—6 of Fig. 3; and

Fig. 7 is a view corresponding to Fig. 2 but illustrating a slightly modified construction.

The device, as illustrated in the drawings, comprises a main or primary hopper or supply chamber 8 having in its bottom a slidably adjustable discharge gate 9 that controls the flow of the grain under the action of gravity from the opening in the hopper to an inclined discharge spout or runway 10. Spout 10 delivers to a secondary hopper or receiving chamber 11 having an inclined bottom and a discharge controlling gate 12. The two hoppers 8 and 11 and spout 10 are, as shown, rigidly secured to cast side frames 13 which have slots or channels in which the gates 9 and 12 are arranged to move and by which said gates are guided.

The primary gate 9, as shown, is arranged to be adjustably secured in different adjustable positions by eccentrics 14 pivoted to legs on the side frames 13 and frictionally engageable with the end portions of said gate. The secondary gate 12, at its projecting ends, is shown as provided with tooth-engaging perforations 15 that are engaged by the teeth of gear segments 16 pivoted on the ends of the transverse rock shaft 17 that is mounted in the side frames 13. Rigidly secured to the ends of the rock shaft 17 and immediately adjacent the gear segments 16 are arms 18 formed with segmental slots 19. Bolts 20 are rigidly secured to the intermediate portions of the gear segments 16, work through the slots 19 and are provided with nuts 21 which, when tightened, adjustably clamp the segments 16 to the respective arms 18. With this arrangement, oscillations of the rock shaft 17 operating through the elements 16 and 18 will raise and lower the gate 12, and adjustments of the bolts 20 in

the slots 19 serve to set the gate in proper horizontal position or parallel to the upper line of the discharge passage from the secondary hopper. As a means for setting the rock shaft 17 and hence the gate 12 in different positions of adjustment, one of the arms 18 is provided with an upper extension 18^a that is formed with a segmental slot 22 and with an indicator finger 23. Finger 23 is adapted to co-operate with graduation marks 24 on the adjacent side frame 13, and to more readily adapt said finger for use as a lever extension to operate the rock shaft and gate it is shown as provided with an offset gripping flange 23^a.

In the commercial machine here described, the drum-like rotary scalping screen is arranged to intercept the grain and other stock coming from the primary hopper through the spout 10 on its way to or toward the secondary hopper. This drum-like screen comprises heads 25 and a heavy very coarse mesh cylindrical screen, preferably a woven wire screen, 26, the said elements 25 and 26 being rigidly connected and the heads 25 being rigidly secured to a transverse shaft 27 journaled in suitable outwardly offset bearings 13^a on the side frames 13. The shaft 27 is shown as provided at one end with a sprocket 28 adapting it and the rotary screen to be driven from a power-actuated belt or chain, but of course said rotary screen may be driven in any suitable way. The drum-like screen is thus arranged to rotate on an approximately horizontal axis and the screen 26 is arranged to run so close to the lower edge of the spout 10 that all of the stock or at least all of the coarse materials will be thrown into engagement or caused to run into said screen. In fact, the meshes of the screen are so coarse that said screen offers but very slight if any resistance to the flow of wheat, oats or similar grain therethrough, first, into the interior of said screen and from thence downward and outward through the screen into the secondary hopper.

To hold back the grain and thereby prevent the same from flowing outward beyond the upper edge of the hopper 11, a stop plate or board 29 is suspended or supported within said screen; and, as shown, this is accomplished by providing said stop plate with a U-shaped hanger flange 30 loosely placed over the shaft 17 and by providing the lower portion of said plate with a weight bar 31 which will serve to prevent said plate from being rotated by the frictional contact between the shaft 17 and hanger flange 30.

The device so far described in detail will perform the scalping function, but to cause the machine to operate also as a cleaner or aspirator, the discharge passage from the secondary hopper controlled by gate 12 is arranged to discharge into an upright air

stack 32, the upper end of which, as shown, is curved and connected to the air intake spout 33 of a power-driven suction fan 34. The air stack 32, as shown, is as wide as the hopper 11 and is rigidly secured to the side frames 13 and hence supported thereby.

6 To control the strength of the air current drawn upward through air stack 32, the latter is provided with an adjustable damper 10 or hinge choke valve 35 that may be arranged to be set in different positions by any well-known means.

The construction illustrated in Fig. 7 is like that already described in connection 15 with the other views except that the discharge gate 12, which may be assumed to receive vertical movements by the means described in connection with the gate 12 but also by any suitable means, is at its upper 20 edge connected by a hinge 36 to an oblique angularly adjustable section 37 of the bottom of the hopper 11. This adjustable bottom plate 37 at its upper edge is arranged to slide on guide flanges 38 formed on the 25 side plates 13 and be set near to or further from the upper edge 11a of discharge passage from hopper 11. In this arrangement, the bottom plate 37 forms a part of the discharge gate structure and it is the structure 30 preferable to that described in the other views for the reason that no pocket is left at the bottom of the hopper 11 for the lodgment of grain.

It will be noted, by reference particularly 35 to Figs. 2 and 7, that the upper hopper delivers against the upwardly moving portion of the rotary screen at a point below the horizontal plane of the axis of said screen, and that the lower hopper extends backward or outward under the bottom of the 40 rotary screen to a point outward of the vertical plane of the axis of said screen. The above noted arrangement of the discharge from the upper hopper delivers the stock 45 against a very considerable portion of the upwardly moving half of the screen and the noted arrangement of the lower hopper serves to hold back the stock and at least assists in causing the same to accumulate within 50 the screen down to or approximately to the bottom of the screen. These two actions greatly increase the efficiency of the separating action and give the cross bars of the screen the best kind of a chance to engage the elongated objects and to turn the same out of the line of the stream so that they will be carried off over the screen.

Operation.

60 The operation, in a general way, has been indicated but may be summarized as follows:

The commingled stock, assumed to be wheat and oats mixed with various large foreign materials, such as stalks, pieces 65 of twine, bark, corn cobs, dust, small

seeds, and frequently nails, pieces of iron, twigs and the like, will be delivered into the primary hopper 8 and from thence will be fed to the rotary drum-like scalping screen under the control of the primary feed gate 70

9. The said scalping screen will be rotated at quite slow speed in a counterclockwise direction in respect to Fig. 2. All of the said materials, except the longer particles, such as straws, bark, cobs, nails, binding twine, and the like, will be engaged by the rotating screen, but will not pass therethrough to the interior thereof for the reason that they will be up-ended or turned upward and deposited on the exterior of the upwardly moving portion of said screen and thereby carried over the top of the screen and discharged at the outer side thereof substantially as illustrated in Fig. 2. In practice, I have found that long or extended particles or objects, such as noted, will not at any time pass through the rotating screen to the interior thereof. All of the smaller particles, such as the wheat, oats, small seeds, dust and the like, will pass freely through the screen to the interior thereof and from thence downward again through the lower portion of said screen into the secondary hopper 11. The grain in the interior of the rotating screen will bank up against the stop plate 29 and, of course, the latter will be held against rotation. This banking up of the stock within the rotating screen is important. It prevents too rapid flow of the stock through the upwardly moving upper portion of the screen and holds back the long objects so that they will be engaged and turned upward by the screen. If the stock were allowed to flow too quickly through the upwardly moving portion of the screen, some 95 of the objects might pass completely through the meshes of the screen and, hence, get into the secondary hopper. Also, the banking up of the stock makes it unnecessary to extend the secondary hoppers far under the rotating screen as would otherwise be necessary.

100 The commingled stock freed from the long objects, as noted, will, under control of the secondary feed gate 12, be fed into the air stack 32 and the air current drawn upward through the latter will pick up all of the lighter materials, such as chaff, light seeds, dust and the like, while the good seeds, such as wheat and oats, will fall downward through said air stack. The cleaned stock, dropping through the air stack, we have assumed to be wheat and oats, but it might be either one of the two grains or some other material. If wheat and oats, the mixture 115 will be in condition for delivery to a suitable wheat and oats separator, such as the well known commercial fanning mills or the disc type of separator well known to the trade as the Carter-Mayhew separator. If 120

125 the mixture is not in condition for delivery to a suitable separator, it may be delivered to a suitable separator, such as the well known commercial fanning mills or the disc type of separator well known to the trade as the Carter-Mayhew separator. If 130

small seeds remain with the clean grain, they can be easily separated out by the use of a fine mesh screen or other suitable means.

The efficiency of this machine has been 5 thoroughly demonstrated in actual practice. The preferred form of the machine has been illustrated and the same has been quite specifically described, but it will, of course, be understood that the machine is capable of a 10 large range of modification, all within the scope of my invention as herein disclosed and claimed.

What I claim is:

1. A scalping machine comprising a drum-like rotary screen, means for delivering commingled stock in compact mass against said screen, and means for causing the stock to accumulate in compact mass within said screen, whereby said screen will tail over 20 large and long foreign substances, while the main stock will pass through said screen to the interior thereof, and from thence out of said screen.

2. A scalping machine comprising a drum-like rotary screen mounted to rotate on a substantially horizontal axis, means for delivering commingled stock in compact mass against the upwardly moving portion of said screen, and means for causing the stock to 30 accumulate in compact mass within and below said screen, whereby said screen will tail over the large and long foreign substances, while the main stock will pass through the upwardly moving portions of the screen to 35 the interior thereof, and from thence through the bottom of said screen.

3. A scalping machine comprising means for directing the flow of commingled stock, a drum-like rotary screen in the path of 40 movement of said stock and serving to tail over the long and large foreign substances, while the main stock relieved therefrom will pass through said screen to the interior thereof, and from thence again through 45 said screen to the exterior thereof, and an upright stop plate mounted within said rotary screen.

4. The combination with a drum-like screen mounted to rotate on an approximately 50 horizontal axis, of stock-supplying means arranged to deliver a regulated flow of the stock against the upwardly moving portion of said screen, and stock-accumulating means located below said screen and 55 provided with a regulated discharge to hold back the stock and cause the same to accumulate within said screen.

5. A scalping machine comprising a coarse 60 mesh drum-like screen mounted to rotate on an approximately horizontal axis, means for delivering commingled stock against the upper portion of the upwardly moving side of said screen, a receptacle below said screen, having a discharge passage that affords a 65 discharge more restricted than the supply

afforded by said stock-delivering means, said screen serving to tail over long and large foreign substances while the main stock relieved thereof will pass through said screen to the interior thereof and thence 70 downward through said screen to the receptacle below said screen.

6. A scalping machine comprising a coarse mesh drum-like screen mounted to rotate on an approximately horizontal axis, means 75 for delivering commingled stock against the upper portion of the upwardly moving side of said screen, a receptacle below said screen, said screen serving to tail over long and large foreign substances while the main stock relieved thereof will pass through said screen to the interior thereof and thence 80 downward through said screen to the receptacle below said screen, and within said screen an upright stop plate arranged 85 to cause the stock to bank up within said screen.

7. A scalping machine comprising a drum-like rotary screen, means for delivering commingled stock in compact mass against said screen at a point below the axis of said screen, and means for causing the stock to accumulate in compact mass within said screen, whereby said screen will tail over 90 large and long foreign substances, while the main stock will pass through said screen to the interior thereof, and from thence out of said screen.

8. A scalping machine comprising a drum-like rotary screen mounted to rotate on a substantially horizontal axis, means for delivering commingled stock in compact mass against the upwardly moving portion of said screen, and a hopper below said 100 screen having a discharge passage arranged to cause the stock to accumulate in compact mass within said screen, said hopper being extended under said screen to a point 105 outward of the vertical plane of the axis thereof.

9. The structure defined in claim 1 in further combination with a stop plate mounted within said rotary screen and gravity-held in an upright position.

10. A scalping machine comprising a drum-like screen mounted to rotate on an approximately horizontal axis, an upper primary hopper having an inclined discharge spout arranged to direct the commingled stock in compact mass against the upwardly moving upper portion of said screen, and a secondary hopper located below the said screen, said screen serving to tail over the large and long foreign substances while the main stock relieved thereof will pass through said screen to the interior thereof and from thence through the lower portion of said screen into said secondary hopper, said secondary hopper having a discharge passage arranged for a more restrict- 115 120 125 130

ed flow of stock than that afforded by the discharge spout of said upper hopper.

11. The structure defined in claim 10 in further combination with an upright baffle plate located within said screen and serving to cause the stock to bank up within said screen.

12. The structure defined in claim 10 in which said rotary screen has an axial shaft, and in further combination with an upright stop plate located within said screen and gravity-suspended on the shaft thereof.

13. The structure defined in claim 10 in which the delivery spout from said primary hopper and the bottom of said secondary hopper incline in opposite directions, and in further combination with an upright stop plate located within said rotary screen and opposing the flow of the stock from the discharge spout of said primary hopper.

14. The structure defined in claim 10 in which the delivery spout from said primary hopper and the bottom of said secondary

hopper incline in opposite directions, and in further combination with an upright stop plate located within said rotary screen and opposing the flow of the stock from the discharge spout of said primary hopper, and in still further combination with an air stack into which the stock is delivered from said secondary hopper, and means for producing an upward flow of air through said air stack.

15. A scalping machine comprising an endless moving screen, means for delivering commingled stock to said screen, and flow-restraining means for causing the stock to accumulate in compact mass against the exterior and interior of said screen, whereby the screen will tail over large and long foreign substances while the main stock will pass through said screen.

In testimony whereof I affix my signature.

CLARENCE W. CARTER.
